UNITED STATES PATENT OFFICE

JOHN P. EATON, OF DES PLAINES, ILLINOIS

DESIGN FOR A TABLE TENNIS GOLF BOARD

Application filed February 18, 1933. Serial No. 47,249. Term of patent 7 years.

To all whom it may concern:

Be it known that I, JOHN P. EATON, a citizen of the United States, residing at Des Plaines, in the county of Cook and State of Illinois, have invented a new, original, and ornamental Design for a Table Tennis Golf Board, of which the following is a specification, reference being had to the accompanying drawing, forming part thereof.

The figure is a plan view of a table tennis golf board, showing my new design.

I claim:

The ornamental design for a table tennis golf board, substantially as shown.

JOHN P. EATON.
